(57) **CLAIM**

The ornamental design for a bed, as shown and described.

DESCRIPTION

FIG. 1 is a perspective view of a bed in a flat and lowered position showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side view thereof;

FIG. 7 is a left side view thereof;

FIG. 8 is a front elevational view of the bed in a flat position showing an alternate embodiment of my new design;

FIG. 9 is a rear elevational view of FIG. 8;

FIG. 10 is a bottom plan view of FIG. 8;

FIG. 11 is a right side elevational view of FIG. 8;

FIG. 12 is a left side elevational view of FIG. 8;

FIG. 13 is a top plan of the bed in a flat position with the mattress removed of FIG. 1, for clarity of illustration only;

FIG. 14 is a top plan view of the bed with the mattress and wheelchair portions removed of FIG. 1, for clarity of illustration only;

FIG. 15 is a perspective view of the bed with the wheelchair portion in an upright position of FIG. 1;

FIG. 16 is a perspective view of the bed with the bed removed showing the wheelchair portion of FIG. 1;
